United States Patent Office.

JAMES W. CAMPBELL, OF NEW YORK, N. Y.

Letters Patent No. 109,494, dated November 22, 1870.

IMPROVEMENT IN GLUING-HOPPERS.

The Schedule referred to in these Letters Patent and making part of the same.

To all whom it may concern.:

Be it known that I, JAMES W. CAMPBELL, of the city, county, and State of New York, have invented a new and useful Improvement in Gluing-Hoppers, of which the following is a full, clear, and exact description, reference being had to the accompanying drawing forming part of this specification, and in which—

Figure 1 represents a plan of a gluing-hopper constructed in accordance with my improvement, and as applied to a groove frame or molding;

Figure 2, a transverse section of the same; and

Figure 3, a transverse section of a tongue-and-groove molding forming portion of a picture-frame, in illustration of one description of work to which my improvement is applicable.

My invention has reference to gluing-hoppers for uniting tongued-and-grooved work, including picture-frames and moldings, formed of strips or pieces fitting by a tongue, the one within or along the other.

As in other hoppers for such purposes, the object of the invention is to effect a uniform and proper distribution of the glue over the surface or surfaces to be coated with it, before inserting the tongue in the groove of the joint, and to this end I use a distributing-hopper, made capable of being slid and guided over the groove, for evenly smearing with glue the sides and top surfaces or upper margins of the groove within and against which the tongued portion of the work is designed to fit.

In my improved hopper, however, I am enabled to dispense with all obstruction or projection from its bottom, such as a guide-strip and regulator, to fit and travel within the groove, and do away with an open construction of the bottom of the hopper throughout its length, which effects a prolonged and unequal distribution, and use instead a hopper having a close bottom with perforations in it, arranged to distribute the glue from fixed or isolated points down the sides of the groove and over the top surfaces or margins of it, free from any interference of a regulating-strip within the groove.

Referring to the accompanying drawing—

A and B represent two moldings or strips used in the formation of a picture-frame, the one strip A being made with a tongue, *a*, and the other strip, B, with a groove, *b*, to secure the fit of the strips to-

gether by gluing them, and for which purpose it is desirable that there should neither be a too thin nor yet too profuse distribution of the glue, but that the same should be evenly distributed over the sides of the groove and top or outer surfaces *c c* of the strip B, along either edge of the groove, free from lodgment of the glue in the bottom, so that on fitting the tongued strip A to its place it will form a close and evenly glued joint with the grooved portion B.

To this end I construct the hopper C, into which the liquid glue is put, with a close bottom, and of a proper form to secure its being guided, when slid over the strip B, in a straight line or course with the groove *b*, and which may be effected by outside guides or strips *d d*, made to fit the molding outside of the groove.

In the bottom of said trough or hopper, at suitable distances apart to insure escape of the glue onto the surfaces *c c* and sides of the groove *b*, I insert apertures *e f* of a size to correspond with the width of the surfaces *c c*, and which apertures are so disposed that they not only lie over the surfaces *c c*, but also slightly overlap the edges of the groove, so that glue in escaping from them will not only smear or coat the surfaces *c c*, but also the sides of the groove.

A hopper thus constructed will, on being slid over the groove of the tongue-and-groove joint, effect a most perfect and even distribution of the glue throughout the length of the joint.

Of course the sizes and distance of the apertures *e* and *f* apart will depend upon the width of the groove and of the marginal surfaces *c c*.

I do not claim a hopper with an open bottom and guide-strip running in the groove, as in patent No. 91,414; but

What is here claimed, and desired to be secured by Letters Patent, is—

A gluing-hopper, constructed with small apertures *e* and *f* in its bottom, near one end, arranged to distribute the glue on the flat surfaces of the molding, and slightly to overhang the groove, substantially as shown and described.

J. W. CAMPBELL.
